C. S. ALVERSON.
 ADJUSTING APPLIANCE FOR TYPE WRITING MACHINES.
 APPLICATION FILED DEC. 2, 1907.
941,294. Patented Nov. 23, 1909.

UNITED STATES PATENT OFFICE.

CAREY S. ALVERSON, OF SAN DIEGO, CALIFORNIA.

ADJUSTING APPLIANCE FOR TYPE-WRITING MACHINES.

941,294.

Specification of Letters Patent. Patented Nov. 23, 1909.

Application filed December 2, 1907. Serial No. 404,654.

To all whom it may concern:

Be it known that I, CAREY S. ALVERSON, a citizen of the United States, residing at San Diego, in the county of San Diego and 5 State of California, have invented a new and useful Adjustable Attachment for Type-Writing Machines, of which the following is a specification.

My invention relates to improvements in a 10 platen for a typewriter to which the paper is applied for the purpose of writing. The platen is provided with adjustable worm and gear shifting attachments for the purpose of systematically adjusting the paper 15 for replacing a figure or letter after the paper has been removed from the typewriting machine and returned again. With this adjustable platen appliance, and attachments, the user may quickly return a paper 20 to the machine and adjust it to the proper position for replacing one or more letters as the occasion may require, and by the aid of the indicator, which is part of the adjustable appliance, it is possible to very accurately and quickly move the platen into 25 position which is shown by the indicator needle or pointer when it is in perfect line horizontally or in a perfect position vertically for re-inserting any figure or letter 30 that it may be desired to replace therein. I attain these objects by the mechanism illustrated in the accompanying drawings, in which—

Figure 1 is a broken front elevation of 35 parts of a typewriting machine showing my attachments thereto. Fig. 1^a is a sectional view of the paper finger or pointer. Fig. 2 is a top plan view of the parts shown in Fig. 1. Fig. 3 is a detail view of the arm 40 for adjusting the platen longitudinally, and Fig. 4 is a detailed sectional view on the line x—x of Fig. 1.

Similar letters refer to similar parts throughout the several views.

45 A is a platen to which the adjustable improvements are attached.

B is the shaft which is inserted through the center of the platen A and has on either end a wheel C which is used for turning 50 the platen back and forth when desired to be moved rapidly.

The lever D and wheel E are elements of 55 the line spacing appliance such as is now employed on typewriters but which does not constitute part of my invention.

F indicates parts of the frame of the car-

riage which holds the platen and other working parts in position.

G is a set screw which is intended to fasten wheel C on to shaft B, firmly and 60 prevent it from working loose or coming off.

The part of the frame or bracket F is provided with a slot R running transversely to the platen shaft. An auxiliary shaft K extends through said slot and carries a 65 worm H on its lower end adapted to mesh with a gear J on the platen shaft. Said auxiliary shaft is also provided with a button N on its upper end, a fixed collar L arranged below the slot R and a movable 70 collar L¹ arranged above said slot and pressed by a spring M abutting at its opposite ends against said movable collar and the button N. Lugs R are formed on the upper surface of the bracket F, midway of the slot 75 R, for the purpose of holding the shaft K in one end of the slot or the other. The position of this slot may be changed by raising the spring pressed collar L¹. It will be noted that when the auxiliary shaft is arranged in the right hand end of the slot, as shown in Fig. 4, the worm H will be out of mesh with the gear J thereby allowing the platen shaft to revolve freely during the operation of the typewriter. It will also be 80 noted that the moving of the auxiliary shaft to the left hand end of the slot will bring the worm H into mesh with the gear J permitting the platen shaft to be revolved by 85 turning the button on the end of the auxiliary shaft for the purpose of fractional line spacing.

O designates two keys whereby the platen A is splined on the shaft B and said platen is adapted to slide longitudinally on said 90 shaft freely and without binding.

An arm P is provided with a forked end P¹ and is mounted on the screw-threaded portion R of the shaft Q as shown at U in Fig. 2. Said forked end P¹ engages a 100 groove in the collar or sleeve A¹ on the platen.

S is a button to turn shaft Q, which slides or moves the platen A longitudinally to a proper adjustment.

T is a collar on the end of shaft Q which holds it in position.

V is an indicator or pointer which indicates the proper position of the paper for re-inserting the letter, that works in conjunction with the adjustable appliance.

W is a casing which holds a spring Z in

connection with indicator V. Said spring engages a groove Y on the shaft X.

I am aware that prior to my invention some of the different parts of the typewriting machine shown here in the drawings which form a part of the specification to my improvements have been patented, and therefore, do not claim those parts to be new and patentable, but simply show them as parts of the typewriting machine to which my improvements are attached all of which are intended to work in conjunction with each other for the purpose of accomplishing the objects set forth in the specifications.

15 I claim:

1. In a typewriter, the combination, with the carriage, of the platen carrying shaft, the platen splined on said shaft, another shaft arranged parallel to the platen and 20 having a screw threaded portion, an arm mounted on said screw threaded portion of said shaft and having its end forked and

engaging a groove in a sleeve on said platen, and means to rotate said second shaft for the purpose of moving said platen longitudinally on said carriage.

2. In a typewriter, the combination, with the carriage, of the platen carrying shaft, the platen splined on said shaft, another shaft arranged parallel to the platen and 30 having a screw threaded portion, an arm mounted on said screw threaded portion of said shaft and having its end forked and engaging a groove in a sleeve on said platen, means to rotate said second shaft for the 35 purpose of moving said platen longitudinally on said carriage, and means to revolve said platen for the purpose of fractional line spacing.

CAREY S. ALVERSON.
